DETACHABLE CLEAT

Filed Dec. 18, 1928

UNITED STATES PATENT OFFICE

WILLIAM H. ALBEE, OF MARLBORO, MASSACHUSETTS, ASSIGNOR TO KOEHLER MANUFACTURING COMPANY, OF MARLBORO, MASSACHUSETTS, A CORPORATION OF MASSACHUSETTS

DETACHABLE CLEAT

Application filed December 18, 1928. Serial No. 326,761.

This invention relates to cleats for football shoes and similar footwear. Each of the regular players of the more important football teams usually is supplied with at least two pairs of shoes, one equipped with short cleats for use on a dry field, and another with much longer cleats for use on a muddy field. Many players, however, are not so well supplied with shoes, and in order to enable such players to meet different playing conditions detachable cleats have been proposed and have gone into use to some extent. Most of these cleats include a body molded around a stud having a screw threaded shank which is detachably mounted in a metal base anchored to the bottom of a shoe. These cleats are made in different heights or lengths, and a player can use either a short cleat or a mud cleat, as he desires. These molded cleats, however, are very likely to break off during a game thus leaving the metal stud exposed. The presence of such studs is highly objectionable and involves an unintentional violation of the rules.

The present invention is especially concerned with this problem, and its aims to devise a detachable cleat which will be more sturdy and substantial than prior constructions, and to provide a cleat-holder which will secure the cleat in such a manner that projecting metal parts dangerous to another player will not be left exposed in the event that a cleat is broken off.

The nature of the invention will be readily understood from the following description when read in connection with the accompanying drawing, and the novel features will be particularly pointed out in the appended claims.

In the drawing,

Figure 1 is a perspective view of the bottom of a shoe equipped with cleats embodying this invention;

Fig. 2 is a plan view of one of the cleats and the holder therefor shown in Fig. 1;

Fig. 3 is a vertical sectional view on the line 3—3, Fig. 2;

Fig. 4 is an exploded perspective view of the cleat and holder construction shown in Figs. 1, 2 and 3;

Fig. 5 is a plan view of a modification; and

Fig. 6 is a sectional view on the line 6—6, Fig. 5.

Referring first to Figs. 2, 3 and 4, the cleat 2 is of frusto-conical form and preferably is made of a series of lifts of leather cemented together and further held in their united relationship by several nails 3 driven through the cleat from top to bottom and clinched on the bottom of the cleat.

This cleat is mounted in a holder which comprises a metal base 4 set into an aperture formed through the tap, heel lift or other tread member 5 of the bottom of the shoe. The base preferably is secured to the outsole 6 of the shoe by rivets 7 which extend through the bottom member of the base. As clearly shown in the drawing the base is provided with a relatively deep socket surrounded by a circular flange which is internally screw threaded. An externally threaded collar 8 is screwed into this socket and grips the lower part of the cleat 2, the collar being internally tapered to fit the tapered base of the cleat. Both the cleats and collars can readily be made very accurately without excessive expense so that the collar will fit tightly on the lower portion of the cleat and secure it rigidly in the base 4 while leaving the greater part of the cleat projecting beyond the collar and entirely free from it. Notches 9—9 are formed in the collar at opposite sides thereof to receive a spanner wrench by means of which the collar may be threaded into or out of the socket in the base.

It will be clear that this construction will securely hold either a long or short cleat, that cleats of one length can be quickly substituted for those of another, and that even if a cleat

should be broken off there are no metal parts left projecting any substantial distance from the sole and which would be liable to injure another player. Furthermore, because of the 5 construction of the cleats they are much less liable to break off than are the molded cleats.

Fig. 1 illustrates a typical arrangement of the cleats, although they may be arranged in any suitable manner.

10 The cleat holder shown in Figs. 5 and 6 is designed to be riveted to the tap, heel lift, or other outer tread member of the shoe bottom instead of being secured to the outsole of the shoe. In this construction the base 4' is provided with ears 10 which are punched to receive rivets 12 by means of which the base is anchored to the tread member 5. This base has an internally threaded socket to receive a collar 8 of the construction shown in Figs. 2, 3 and 4. These base members 4' may be located in and riveted to the tap sole, heel lift, or other tread member, and this member later may be nailed, stitched or otherwise secured to the bottom of the shoe. Usually it 25 is preferable to have the lower surface of the cleat project very slightly beyond the inner surface of the collar so that when the collar is screwed into the socket it will force the lower surface of the cleat against the bottom of the socket and thus compress the stock slightly. This compression assists in locking the collar in place and preventing it from working loose.

While I have herein shown and described 35 preferred embodiments of my invention, it will be understood that the invention may be embodied in other forms without departing from the spirit or scope thereof. For example, other forms of tapered cleats may be 40 used, the tapered aperture in the collar 8 being correspondingly shaped to fit the outline of the cleat as well as to conform to the taper of the base portion of the cleat.

Having thus described my invention, what 45 I desire to claim as new is:

1. A device of the character described comprising a base adapted to be secured to the bottom of a shoe, said base having a screw threaded socket therein, a tapered cleat, and 50 a collar in which the lower part of said cleat is held, said collar being internally tapered to grip the tapered surface of said cleat while leaving the greater part of the cleat projecting beyond the collar and being externally 55 screw threaded to screw into said socket, the collar being constructed for the application thereto of a tool to screw it into or out of said socket.

2. A device of the character described comprising a base adapted to be secured to the bottom of a shoe, said base having a screw threaded socket therein, a tapered cleat having 60 nails extending therethrough from top to bottom and clinched, and a collar externally 65 screw threaded to fit in said socket and in-

ternally tapered to receive and grip the tapered base of said cleat but leaving the greater part of the cleat projecting beyond the collar.

3. In a shoe having a bottom comprising a tread member having an aperture there-through, a metal base secured to said bottom adjacent to said aperture and provided with a flanged portion fitting in and projecting substantially through said aperture, said flange surrounding a socket, a collar detachably fastened in said socket, and a tapered cleat held by said collar, said collar being internally tapered to fit snugly around and grip the base portion of said cleat but leaving the greater portion of the cleat projecting beyond the collar.

4. In a shoe having a bottom comprising a tread member having an aperture there-through, a metal base secured to said bottom and provided with a socket surrounded by an internally screw threaded flange located in said aperture, an externally threaded collar removably fitting in said socket, and a tapered cleat held by said collar, said collar being internally tapered to grip the base of said cleat while leaving a considerable portion of the cleat projecting beyond the collar and having recesses in its outer edge to receive a tool for screwing it into or out of said socket.

5. A device of the character described comprising a base adapted to be secured in a recess formed in the bottom of a shoe, said base having a screw threaded socket therein, a tapered cleat comprising a plurality of lifts of leather or the like with metallic fastenings extending through said cleat from top to bottom thereof and clinched to hold said lifts together, a collar internally tapered to grip the tapered surface of said cleat, said collar being externally threaded to screw into said socket and having recesses in the edge thereof to receive a tool to screw it into or out of said socket.

6. A detachable cleat construction comprising, in combination, a base adapted to be secured to the bottom of a shoe, a tapered cleat, a collar in which the lower part of said cleat is held, said collar being internally tapered to grip the larger end of the cleat while leaving the greater portion of the cleat projecting beyond the collar, and said collar and base having cooperating screw threaded portions for securing them together and forcing the bottom face of the cleat against said base to bind the cleat in its operative position.

7. In a detachable shoe cleat, a plate having a threaded portion for attachment to the sole of a shoe, a rigid, non-collapsible cleat formed as a cone, and a threaded locking ring encircling the cleat and engaged with the threaded portion of the said plate to secure the cleat in position upon the sole of the shoe.

8. A detachable shoe-cleat formed as a rigid, non-collapsible cone and having attached at its base a metal part which embraces the tapering sides of the cone near its base to secure the parts together in fixed relation, the said metal part constituting the means through which the cleat may be attached to the sole of a shoe, and whereby the cleat may be detached without disturbing any permanently fixed fastening means.
